METHOD FOR PACKAGING FILAMENTARY MATERIAL

Graeme G. Whytlaw, Swarthmore, Pa., assignor to American Viscose Corporation, Wilmington, Del., a corporation of Delaware

Application May 26, 1947, Serial No. 750,530

2 Claims. (Cl. 53—4)

1

This invention relates to improvements in methods for packing filamentary material. In the practice of the prior art of applying a protective covering member to hollow or annular bodies of filamentary material such as cakes of yarn, thread and the like filamentary material, considerable time and manipulation was required to apply the covering to the filamentary material and often during liquid treatment or subsequent manipulation the covering became disarranged and damaged with accompanying damage to the filamentary material.

This invention has for its principal object to provide improvements in methods for packaging filamentary material that overcome objections and disadvantages found in the prior art. Another object of the invention is to provide simplified methods for applying protective covering members to hollow bodies of filamentary material that are economical and that result in improved filamentary material packages.

Other objects and advantages of the invention will be apparent from the following description and accompanying drawing.

In the drawing, which is illustrative of the invention, reference is made to the following figures:

Figure 1 is an elevational view of a covering as first applied to a support therefor.

Figure 2 is an elevational view of the covering on the support after the upper portion of the covering has been rearranged.

Figure 3 is an elevational view with parts shown in section of the support and covering apparatus with a body of filamentary material placed thereon.

Figure 4 is an elevational view showing an intermediate step of applying the covering to the body of filamentary material.

Figure 5 is an elevational view showing the covering as applied to the filamentary material with parts shown in section.

Figure 6 is a perspective view showing a filamentary package embodying this invention.

In accordance with the practice of the present invention a covering member first formed of a sheet of permeable paper-like material having a good wet strength is applied to a hollow or annular package of yarn, thread or the like filamentary material such as a rayon cake by passing the sheet material in tubular form through the inside of the body of filamentary material and positioning the end portions of the sheet material in overlapping relation against the outside. Paper or paper-like materials made from natural fibers such as wood, cotton, hemp, linen,

2

abaca or from artificial fibers such as cellulose acetate or regenerated cellulosic fibers that are obtainable from viscose or cuprammonium cellulosic solutions, from about $\frac{1}{8}$ inch to one inch or longer, having high wet strengths may be used. Permeable paper having increased wet strength as the result of resin impregnation during or subsequent to its formation into a sheet is also suitable. Paper of the latter type may be formed from fibers either of paper making length or greater than normal paper making length and may be impregnated with urea, formaldehyde, phenol-formaldehyde, melamine-formaldehyde resins or with solutions of cellulose or cellulose derivatives, such as cellulose acetate, viscose or the like. Also paper-like sheet materials may be used that are of a thin matt-like construction containing potentially adhesive fibers, admixed with non-adhesive fibers and that have been activated to bond the fibers together to produce a paper-like material of high strength. Permeable thin fibrous matt-like constructions having improved wet strength as the result of increased binding, brought about by the partial parchmentizing action of dilute solutions of strong chemicals such as sulphuric acid or caustic soda or as a result of impregnating with resin, viscose or other permeable binding solutions during or subsequent to the formation of the sheet are also suitable.

In practicing the invention the paper-like sheet material to comprise the covering member is first formed into a tube by overlapping its lateral edges. The overlapping portions may be secured by adhesive material or sufficient overlap may be provided so that additional securing means is not necessary. The tubular sheet material is then passed through the inside of the filamentary body. As the tubular sheet material must be of greater periphery than the outside of the filamentary body in order for the sheet material to be applied to the outside of the filamentary body, provision must be made for taking care of the excess sheet material that will be on the inside of the filamentary body. It is desirable that the sheet material comprising the covering member closely contact the filamentary material throughout both the inner and outer walls thereof in order to protect the filamentary material and avoid damage to the covering member. In the present invention the portion of the covering member that contacts the inner wall of the body of filamentary material is twisted to form folded overlapping portions that extend in helical paths and the folded portions are posi-

tioned against the inner wall of the filamentary body. It is contemplated that the covering member will be passed through the filamentary body and an end portion of the covering member will be drawn over the means for supporting the filamentary body. The other free end portion of the covering member will be twisted about the axis of the filamentary body to form folded or overlapping portions that extend in helical paths and in effect reduce the diameter of the portion of the covering member adjacent the inner wall of the filamentary body to approximately the inner diameter of the filamentary body. The free end portion of the covering member is opened and partly untwisted and is then drawn over the end of the filamentary body and positioned against the outer wall of the filamentary body. The other end portion of the covering member is then drawn over the other end of the filamentary body in overlapping relation with the first end portion of the covering member. The overlapping end portions may be twisted relative to one another on the filamentary body to tightly place the covering member against the filamentary material. With this procedure the covering member closely contacts all portions of the filamentary body and retains its position thereon during liquid treatment and manipulation of the filamentary body. Due to the folded overlapping portions of the cover member against the inner wall of the filamentary body the covering member is reinforced in this region.

Referring to the drawing in which is illustrated a form of apparatus with which this invention may be carried out and with respect thereto the various steps comprising applicant's method are shown, reference character 1 indicates generally a covering member in tubular form placed in its initial position on the apparatus. The apparatus comprises a circular plate-like member 6 mounted on the vertical standard 7 supported in the base-like member 8 and braced by the bracket member 9. The plate-like member has a depending portion 15 that rests on the bracket member 9 so that the plate member 6 is supported by both the bracket and the standard. The plate member 6 may be either fixed to the standard 7 or may be revolvable thereon. Positioned above the plate-like member 6 on the standard 7 are the cover member gripping and twisting means comprising the members 12 and 13.

As shown in Figure 2, after the covering member in tubular form has been positioned in the apparatus the upper portion is manually gathered in toward the standard and is positioned between the members 12 and 13. The details of the cover gripping and twisting means are shown in Figures 2 and 5. They comprise a collar member 11 fixed to the standard and on which is rotatably mounted the member 12 that is provided with a conical shaped portion. The member 13 is rotatably and slidably mounted on the standard 7 above the member 12. The member 13 is provided with a conical shaped recessed portion that is complementary to the conical portion on the member 12. The member 13 may be rotated and raised on the standard by means of the handle member 14.

When the upper portion of the covering member is gathered in it is positioned between the members 12 and 13. The covering member is gripped between the conical portions of the members 12 and 13, and on rotating the member 13 the covering member is twisted and folded and overlapping portions are formed that extend in

helical paths. Also the diameter of the tubular member above the plate member 6 is reduced as shown in the drawing in Figure 2.

5 A filamentary body, such as a rayon cake 5 is then placed over the covering member and supported on the plate member 6 as shown in Figure 3. The upper portion 4 of the covering member is then withdrawn from between the members 13 and 12 and is opened outwardly and partly untwisted without disturbing the folded overlapping portions of the mid portion 3 of the covering member. The upper portion 4 of the covering member is then drawn over the outer wall of the filamentary body as shown in Figure 15 4. Thereafter the lower portion of the covering member 2 is drawn upwardly over the outer wall of the filamentary body and positioned in overlapping relation against the other end of the covering member. The end portions of the covering member may be twisted around the filamentary body to tighten the covering member on the filamentary body.

20 The resulting package of filamentary material is as shown in Figure 6 with the covering member closely engaging all portions of the filamentary body. As shown the portion 3 of the covering member in engagement with the inner wall of the filamentary body is folded or overlapped in helical paths which in effect reduces the periphery of this portion of the covering member. The folded portion reinforces the covering member in this region and gives it increased resistance to 25 tearing and abrasion.

30 35 While preferred embodiments of the invention have been shown and described, it is to be understood that the description hereinabove is illustrative only and that changes and variations may be made without departing from the spirit and 40 scope of the invention as defined in the appended 45 claims.

I claim:

1. The method of applying a covering member to an annular body of filamentary material having an inner wall and an outer wall comprising positioning a covering member of paper-like sheet material in tubular form in the body of filamentary material with the end portions of the covering member extending beyond the body of filamentary material, gripping the tubular sheet material near one end, twisting the sheet material in a region adjacent the gripped end and the portion adjacent the inner wall of the body of filamentary material to form overlapping portions therein that extend in substantially helical paths, positioning the end portions of the covering member in overlapping relation against the outer wall of the body of filamentary material and twisting the overlapping end portions relative to one another to tightly place the covering member against the filamentary material.

55 60 65 70 75 2. The method of applying a covering member to an annular body of filamentary material having an inner wall and an outer wall comprising supporting a tubular covering member of paper-like sheet material in a generally vertical position with its lower end portion in expanded condition, the expanded tubular member having a periphery greater than the outer periphery of the body to be covered, seizing the upper end portion and gathering it in, imparting relative rotation between the upper and lower end portions to twist the intermediate portion above the lower end portion and in effect reduce the diameter of the intermediate portion to approximately the inner diameter of the body, then passing

the annular body down over the upper end portion into a position around the intermediate portion of the member, untwisting and enlarging the upper end portion to cause the intermediate portion to closely contact the inner wall of the body and positioning the end portions of the covering member in overlapping relation against the outer wall of the body of filamentary material.
